UNITED STATES PATENT OFFICE.

FRANK RUSSEL HARTSOCK, OF WARSAW, INDIANA, ASSIGNOR OF ONE-HALF TO
CHARLES O. DICKEY AND ONE-THIRD TO LEONARD E. DICKEY, OF WARSAW,
INDIANA.

RIM TOOL.

Application filed March 20, 1922. Serial No. 545,071.

To all whom it may concern:

Be it known that I, FRANK R. HARTSOCK, a citizen of the United States of America, and a resident of Warsaw, county of Kosciusko, and State of Indiana, have invented certain new and useful Improvements in Rim Tools, of which the following is a full and clear specification.

The object of this invention is to so construct the apparatus that it will not only be adapted for removing and replacing all types of split rims, but will be capable of quick and easy operation in the removal and replacing of the most troublesome rims, as more fully hereinafter set forth. This application is a continuation in part of my copending application Serial No. 384,939, filed May 28, 1920, renewed August 6, 1923.

In the drawings—

Fig. 1 is a perspective view of my apparatus applied to a tire-rim, the latter being shown in dotted lines:

Fig. 2 is a transverse sectional view on the lines 2—2 of Fig. 1;

Fig. 2 is a vertical sectional view taken through one of the rim-gripping devices, part of the frame and screw expanding and contracting devices being omitted;

Fig. 3 is a plan view, partly in horizontal section, showing the position of the parts after the rim has been expanded, for the purpose of opening the locking device, the expanded rim being shown in dotted lines;

Fig. 4 is a similar view showing the next step in the removal of the rim from the tire, one end of the rim being swung inwardly to disalign it with respect to the other end of the rim;

Fig. 5 is a view similar to Figs. 3 and 4 showing the apparatus in final position, in which the adjacent ends of the rim have been drawn to overlapped position to thus contract the rim sufficiently to detach it from the tire;

Figs. 6 and 7 are detail views of one of the rim-gripping jaws;

Fig. 8 is a section on the line 8—8 of Fig. 2.

Referring to the drawings annexed, I employ a frame consisting of a pair of similarly curved bars 10, connected pivotally together at one end by a vertical bolt 11, and provided each at its other end with a rim-gripping appliance. Each rim-gripping appliance consists of a pair of jaws 12, lying

respectively against the upper and lower flat faces of a head 13 formed integral with the outer end of the bar 10, the jaws being attached to this head by a vertical clamp-bolt 14 extending through longitudinal slots 15 in the jaws and through holes in the ears 16 formed on the head 13, a lever-nut 17 being screwed on the upper threaded end of the bolt 14 and the head 18 of the bolt bearing against the lower side of the lower jaw.

The outer end of each of the jaws 12 is provided with a groove adapted to receive the edge of the rim, this groove being substantially V-shaped so as to bear against both sides of the edge of the rim and thus grip the same firmly. In the inner wall of the groove is riveted an inset consisting of a steel plate 19 having a face which bears against the rim flange and having square corners at its end. The rear ends of each pair of jaws project beyond the supporting head 13 and these rearwardly projecting ends are connected by a coil-spring 20, which spring passes through a hole in an inwardly-extending lug 21 carried by said head. In the face of the head 13, under the rear or inner end of each jaw, is formed a groove 22 curved on an arc struck from the center of the clampbolt 14; and working in each groove is a curved lug 23, formed on the adjacent face of the jaw.

Connected to the bars 10 at a point between the pivot bolt 11 and the rim-gripping devices is a lever-operated appliance for spreading as well as contracting the bars. This appliance is constructed of two similar screws 24, each of which is pivoted to one of the bars by means of a vertical bolt 25, the pivotal ends of the screws, for the sake of compactness, extending into recesses 26 formed in the inner walls of the respective bars. The two screws have their inner ends threaded into the opposite ends of a rotatable sleeve 27, and affixed to this sleeve 27 midway its ends is a ratchet-wheel 28. Pivotally mounted on the sleeve, preferably so as to embrace the ratchet-wheel, is a hand-lever 29, and carried by this hand-lever is a reversible pawl 30 adapted to rotate the ratchet-wheel by operation of the lever 29 in either direction, according to which position the pawl is set in. This reversible pawl is desirably of the spring-actuated snap-over type, the spring 31 being housed in the hand-lever 29, so that the pawl may

not only be quickly shifted, but will remain in its shifted position until it is manually reversed.

The lower end of the pivot bolt 11 depends 5 a short distance beyond the bars 10, and pivotally connected to this depending end of the bolt is the inner link of a chain 32. The other end of this chain is adapted to be pulled laterally by means of a hand-lever 10 33 which is provided at its lower end with a hook 34 adapted to engage in any one of the links of the chains, said lever 33 being provided with a pivotal hook 35 which is adapted to engage over the tire-^{rim} at a 15 suitable point to one side or the other of the joint in the rim, for the purpose hereinafter set forth.

As will be observed, this appliance is adapted to rest upon the floor, so as not only 20 to relieve the operator of the labor of handling it while operating it, but also to enable it to be readily moved about from place to place. The springs 20 normally maintain the jaws in open position, so that all that 25 it is necessary to do to place a rim in the apparatus is to roll the tire into such position that when it is laid down on its side the edges of the rim will rest in the grooves in the lower jaws, the joint in the rim being 30 of course arranged to lie between the two sets of jaws. After the rim is thus placed in the jaws, the lever-nut 17 is screwed up to bring the jaws into clamping relation upon the rim. The next step in the operation 35 with most rims is to separate the abutting ends of the rim, the distance of separation being determined by the character of the rim, as shown in Fig. 3. This is done by operating the hand-lever 29 in 40 such manner as to screw out the screws 24. Then the hook 35 is hooked over the rim of the tire at either side of the wheel, the hook 34 of the lever 33 being engaged in one of the links of the chain 32, the link being selected in accordance with the size of the tire; then by swinging the upper end of the lever 33 inwardly, the frame is tilted to the 45 position shown in Fig. 4, the fulcrum being the right-hand one of the jaw-bolts 14. After the ends of the rim are disaligned in 50 this manner, then (while the operator holds the frame in this tilted position with one hand on the lever 33) the bars are contracted by reversing the pawl 30 and swinging the hand-lever 29 back and forth a sufficient 55 number of strokes to bring the ends of the rim to overlapped position, as shown in Fig. 5, whereupon the rim and tire may be separated from each other. When the tire 60 is to be replaced upon the rim, the operations are the reverse of those set forth for removing the rim, and, in re-aligning the ends of the rim, the tilting appliance (consisting of the lever 33, chain 32 and hook 35) will 65 be reversed, i. e., connected to the rim at

the opposite side, as shown in dotted lines in Fig. 3, to enable the lever 33 to be utilized to force the end of the rim back into alignment with the other end.

It will be observed that when the device 70 is in use, resting on the floor, the heads 18 of the jaw-bolts and the extended end of bolt 11 serve together as a sort of tripod for supporting the apparatus properly on the floor. With this manner of supporting 75 the appliance it will be observed that it will be unnecessary for the operator to sustain the weight of the apparatus while using it, and it will be observed that this three-point support holds the apparatus always 80 in the proper position for manipulating the various parts in removing or in replacing the rim. It will be observed that it is unnecessary to anchor the apparatus to a pedestal or table, as all the strains incident 85 to operating the apparatus are taken up within the apparatus or the rim being operated on. It will be seen that by thus adapting my apparatus for resting on the floor while being used, as distinguished from being supported and handled by the operator, 90 enables me to make the parts of the apparatus as heavy as is needed to provide the necessary strength for manipulating the most troublesome rims. 95

It will be observed that a feature of importance is the means provided for tilting the frame for dis-aligning the ends of the rim. The device I have provided for this purpose is adjustable to all sizes of rims, since the lever 33 may be engaged in any one of the 100 links of the chain. A chain is particularly desirable, since the operator soon learns which link is needed for each particular size of tire on the market and thus is enabled 105 to select readily the adjustment needed. Reversibility of this appliance is also important, since it enables the operator to tilt the frame in either direction by simply shifting the hook 35 to one side or the 110 other of the rim. By means of the hand-lever 33, ample power may be readily applied to the chain to tilt the frame against the resistance of the heaviest rims.

The means for spreading and contracting 115 the bars 10, is an important feature of my appliance. The use of screw devices provides a self-locking arrangement, ensuring the parts being locked in their adjusted positions, and the provision of a reversible 120 pawl enables the bars to be either spread or contracted by the simple forward and backward movement of the hand-lever 29, the ratchet-wheel 28 being supported in a position above the floor by means of the before-described supports 18 and 11.

The slots 15 in the jaws 12, especially in the upper jaws, enable the jaws to swing wide apart to thus facilitate the placing of the rim in the jaws; and the slot-and-lug 130

arrangement 22—23 serves to prevent, or assist in preventing, the jaws sliding either inwardly or outwardly on the heads 13. The springs 20 also assist in holding the 5 jaws from sliding inwardly or outwardly and these springs are particularly advantageous in preventing the inner ends of the jaws from swinging too far in either direction, the perforated lug 21 serving to re- 10 strict lateral swinging of the spring and thus ensuring constant pull on the inner ends of the jaws, tending to properly position them on the heads. The main function, of course, of these springs 20 is to 15 hold the jaws open, or rather hold the upper jaw swung upwardly to the limit of its movement, as shown in dotted lines in Fig. 2^a. When the device is resting on the floor and not in use, the lower jaw, of course, 20 bears solidly against the under face of the head 13, while the upper jaw is held in an elevated position, to thus provide a wide open mouth for the introduction of the rim; when, however, the jaws are brought together upon the rim by means of the hand-nut 17, the head 13, and also the tire will 25 be centered between the jaws, as shown in full lines in Fig. 2^a.

The clamp-bolts 14 are essential not only 30 for operating the jaws, but they also serve as pivotal bolts on which the frame swings when it is laterally tilted, as shown in Figs. 4 and 5. In these figures, it will be observed that the jaws are slightly askew with 35 reference to the heads 13, showing that in tilting the frame there has been a slight pivotal action on the bolts, the bolt at the side toward which the frame is tilted being the one to serve as a fulcrum and take up the 40 thrust. This permitting the jaws to have a slight pivotal play on the bolts is advantageous also for the reason that it ensures the steel insets 19 obtaining the proper biting action on the edge of the rim. I have 45 learned from experience that merely clamping the jaws down against the rim flanges, no matter how hard the clamping action may be, is not sufficient; in addition, I have found that there must be a biting action on 50 the rim in order to prevent the jaws slipping thereon. This biting action I obtain by means of the outer corners of the steel insets 19, which corners are caused to bite into the rim when the jaws are slightly 55 swung on the pivot-bolts 14. This slight pivotal action on the jaw-bolts and the consequent biting action on the rim takes place not only in spreading as well as contracting 60 the rim, but also in tilting it my means of the chain-and-lever arrangement; consequently, I provide for a very secure grip upon the rim in all operations.

To give the floor-engaging lower end of 65 the pivot-bolt 11 a broad bearing on the floor, I screw on the threaded lower end of

the bolt a nut 36, this nut being suitably locked against turning by riveting the end of the bolt or otherwise.

I do not desire to be understood as limiting myself to the precise details of construction and arrangement shown, as variations and modifications therefrom may be made without departing from the spirit and scope of my invention and improvements. I therefore reserve the right to all such variations and modifications as properly fall within the scope of my invention and improvements and as set forth in the terms of the following claims.

What I claim is:

1. In a tire-rim tool, a frame composed of a pair of bars movably connected together at one end and each having a rim-gripper at its other end, means for spreading as well as contracting the bars for the purposes set forth, and means adapted to connect the inner end of said frame to an adjacent point on the rim for tilting the frame edgewise on a fulcrum formed by one of said grippers to thereby swing inwardly one end of the rim.

2. In a rim tool, a pair of bars pivotally connected together at their inner ends, a pair of clamping members carried by the opposite end of each of said bars and adapted to engage with a rim, a hand-operated means connecting said bars at intermediate points thereof for moving said bars toward and away from each other to thereby contract or expand the rim, and a connection between the pivot of said bars and the rim for moving said pivot laterally to thereby move one of said pairs of clamping members inwardly to thus draw the ends of the rim out of alinement.

3. In a rim toll, a pair of bars pivotally connected together at their inner ends, a pair of clamping members carried by the opposite end of each of said bars and adapted to engage with a rim, a hand-operated means connecting said bars at intermediate points thereof for moving said bars toward and away from each other to thereby contract or expand the rim, and a connection between the pivotal point of said bars and the rim, said connection consisting of a hand-lever, a flexible member connecting the lower end of said hand-lever with said pivotal point, and a hook pivotally connected to said hand-lever at a point near the lower end thereof and engaging with the wheel-rim, whereby operation of said hand-lever exerts a pull on said flexible connection to thereby pull inwardly on one of said pairs of clamping members to thus draw the ends of the rim out of alinement.

4. In a rim-tool appliance, a pair of frame bars each provided with a head at one end and being connected together at their other ends, means for spreading as well as con-

tracting said frame-bars, a pair of jaws mounted on each head, one on the under side and the other on the top side, said jaws being longitudinally slotted, a pivot-bolt for each pair of jaws adapted to clamp the jaws to the head, and spring means at the inner ends of the jaws tending to spread apart the other, rim-gripping end of the jaw.

5. In a rim-tool appliance, a pair of frame-bars each provided with a head at one end and being connected together at their ends, means for spreading as well as contracting said frame-bars, a pair of jaws mounted on each head, one on the under side and the other on the top side, said jaws being longitudinally slotted, a pivot-bolt for each pair of jaws adapted to clamp the jaws to the head, and spring means at the inner ends of the jaws tending to spread apart the outer, rim-gripping ends of the jaws, said spring means consisting of a single

10

15

20

spring working through an apertured lug projecting inwardly from the head.

6. In a rim-tool appliance, a pair of frame-bars each provided with a head at one end and being connected together at their other ends, means for spreading as well as contracting said frame-bars, a pair of jaws mounted on each head, one on the under side and the other on the top side, said jaws being longitudinally slotted, a pivot-bolt for each pair of jaws adapted to clamp the jaws to the head, and spring means at the inner ends of the jaws tending to spread apart the other, rim-gripping end of the jaw.

25

30

35

6. In a rim-tool appliance, a pair of frame-bars each provided with a head at one end and being connected together at their other ends, means for spreading as well as contracting said frame-bars, a pair of jaws mounted on each head, one on the under side and the other on the top side, said jaws being longitudinally slotted, a pivot-bolt for each pair of jaws adapted to clamp the jaws to the head, and spring means at the inner ends of the jaws tending to spread apart the other, rim-gripping end of the jaw, the faces of the jaws and the heads being provided with an interlocking groove and lug, the groove being curved on an arc struck from the center of the adjacent pivot-bolt.
